(57) **CLAIM**

The ornamental design for a trigger stick assembly, as shown and described.

DESCRIPTION

FIG. 1 is a perspective view of a trigger stick assembly according to the present disclosure.

FIG. 2 is a detailed perspective view of the upper portion of the assembly of FIG. 1.

FIG. 3 is a detailed left side view of the upper portion of the assembly of FIG. 1.

FIG. 4 is a detailed right side view of the upper portion of the assembly of FIG. 1.

FIG. 5 is a detailed rear side view of the upper portion of the assembly of FIG. 1.

FIG. 6 is a detailed front side view of the upper portion of the assembly of FIG. 1.

FIG. 7 is a detailed top view of the upper portion of the assembly of FIG. 1; and,

FIG. 8 is a detailed bottom view of the upper portion of the assembly of FIG. 1.

Evenly broken lines in FIGS. 1–8 are for environmental purposes and form no part of the claimed design.

1 Claim, 8 Drawing Sheets
